UNITED STATES PATENT OFFICE

2,501,789

SOLE ATTACHING MACHINE

Paul W. Senfleben, Malden, Mass., assignor to
United Shoe Machinery Corporation, Flemington, N. J., a corporation of New Jersey

Application March 17, 1947, Serial No. 735,168

25 Claims. (Cl. 12—33)

1

This invention relates to machines for attaching soles to shoe bottoms and more particularly to the cement attachment of soles to the bottoms of welt shoes.

An object of the invention is to provide an improved machine having provision for activating previously-applied cement on a sole and shoe bottom and then pressing the shoe parts together. For activating the cement on the sole and shoe they are supported in spaced relation and in register with each other and a heat activator is moved into position between them to soften the cement after which the activator is moved out of the way and the sole and shoe are pressed together. The sole is supported by a pad box provided with sole positioning gages. In accordance with one feature of the invention, gages arranged to contact opposite side edges of a sole and the toe end of the sole are provided to determine the widthwise and lengthwise position of the sole thereon, the gages being actuated in a manner to position soles of different lengths in a predetermined location on the pad, there being means for adjusting the side gages independently of the toe gage to accommodate soles of different widths. The toe gage includes gage members which cooperate with the side gages to determine the angular position of the sole on the pad.

In accordance with a further feature of the invention the gages associated with the pad box are arranged to position soles of different sizes on the pad with a reference point within the sole at a predetermined position on the pad, there being means for supporting a shoe above the sole on the pad and in register with it so that after the activation of the cement on the sole and shoe the supporting means therefor may be moved to press the sole against the shoe bottom. By thus positioning the sole it will be in the most desirable position on the pad regardless of its length and the accurate registration of the shoe therewith is facilitated.

Inasmuch as the present machine is particularly adapted for attachment of soles to welt shoes, the supporting means for the shoe, in accordance with a further feature of the invention, includes a welt holddown having a portion engageable in the welt crease of the shoe around the forepart, the welt holddown being adjustable to accommodate shoes of different sizes and to register them accurately with the soles on the pad box. The welt holddown engages the welt around the forepart of the shoe rearwardly to the ball line at each side and the ends of the

5 welt support are made adjustable widthwise of the shoe in accordance with the size of the shoe to be operated upon. Inasmuch as the lengthwise position of the shoe is determined by the position of the welt support, that portion which engages the toe end of the shoe must be moved lengthwise of the pad box for different shoe sizes. The welt support is flexible, being illustrated as formed of a plurality of welt-engaging members yieldingly held in assembled relation but capable of relative movements to vary the contour of the shoe-engaging portion. During the movements of the ends of the welt support widthwise of the shoe one end of the welt support is also moved lengthwise of the shoe thereby determining the lengthwise position of the shoe with respect to the sole on the pad box. In accordance with a still further feature of the invention these adjustments of the welt support are 10 all made simultaneously by a single actuating member, there being means also for individually moving each end of the welt support to adjust it for different widths of shoes.

The above and other features of the invention, including various details of construction and novel combinations of parts will now be described by reference to the accompanying drawings and pointed out in the claims.

In the drawings,

30 Fig. 1 is a front elevation of one form of machine embodying the invention;

Fig. 2 is a front elevation on a larger scale of a portion of the machine shown in Fig. 1;

Fig. 2a is a section on the line IIa—IIa of Fig. 2;

35 Fig. 3 is a plan view on a still larger scale of the gage mechanism by which the outsole is located in a predetermined position on the pad box;

Fig. 4 is a front elevation of the gage mechanism shown in Fig. 3;

Fig. 5 is a section on the line V—V of Fig. 3;

Fig. 6 is a plan view of the pad box with the heating member, by which the cement on the attaching faces of the sole and shoe is activated, positioned thereabove;

Fig. 6a is a detail view of the mounting of the heating member;

Fig. 7 is an end elevation of one of the shoe supports showing a shoe carried thereby;

Fig. 8 is a plan view of the shoe support of Fig. 7 with the top plate removed, and

Fig. 9 is a plan view of the mechanism for adjusting the welt-engaging part of the shoe support.

The invention is illustrated as embodied in a

two-station pressing machine (Fig. 1) of the type shown and described in Letters Patent of the United States No. 1,549,243, granted August 11, 1925, on an application of E. E. Winkley. The machine includes a base 10 on which are bolted two standards 12 each having two pillars 14 (only the front ones of which are illustrated herein). From each pillar rises a rod 16 and at the upper end of each pair of rods, associated with each end of the machine, is a jack 18 vertically adjustable on the rods by means of a screw or other equivalent device 20. Pad boxes 22 are pivoted at 24 in sliding frames 26 on the rods 16 for vertical movement along the rods to move toward and from shoes supported by the jacks 18.

Each sliding frame 26 is moved vertically through a mechanism which comprises an upper toggle link 28 and a lower toggle link 30 pivoted to each other at 32, the upper link being pivoted at 34 to the sliding frame 26 and the lower link being pivoted at its lower end by a pin 36 to the end of a lever 38 pivoted at 40 to a plate 41 which is adjustably supported upon adjustable studs 42 at the front of the machine. The toggle links 30 are connected by a link 44 which is arranged to be moved by mechanism indicated generally by the reference character 46 either to the right or left upon each depression of a treadle 48. Thus upon each depression of the treadle one set of toggle links is straightened and the other set is broken whereby one of the pad boxes moves upwardly to force the sole carried thereby into engagement with the shoe bottom and the other pad box descends to permit removal from the machine of a shoe to which a sole has been attached. Provision is made for providing a spring yield in the mechanism for straightening the toggle links thereby to accommodate soles of varying thicknesses. For a more complete description of the operating mechanism by which the pad boxes are moved vertically along the rods 16 reference may be made to the Winkley patent mentioned above.

The pad boxes 22 on which the outsoles are positioned prior to the pressing operation, and which carry the soles into engagement with the shoe bottom, may be of any suitable construction, those illustrated in Figs. 1 and 2 being of the type shown and described in Letters Patent of the United States No. 2,063,041, granted December 8, 1936, on an application of L. G. Knowles. Associated with each pad box are gages by which the position of the outsole relatively to the supporting surface of the pad box is accurately determined. The gages are so arranged as to position outsoles of different sizes in the same positions on the pad box with regard to the ball line of the sole. In other words, regardless of the size of the sole the center of the ball line will always be in the same position on the pad box.

For thus locating the outsole on the pad box side gages 50 (Fig. 3) and a toe gage 52 are provided. The toe gage includes a central gage member 54 and side gage members 56. The gage members 56 cooperate with the gage member 54 and the side gages 50 to determine the angular position of the sole on the pad box. For mounting the gages and the positioning means therefor on the pad box, a plate 58 is secured to the marginal portion of the toe end of the pad box. This plate is slotted at 60 (Fig. 4) at opposite sides of the pad box to receive slides 62 to which the side gages 50 are pivoted. A torsion spring 70 acts between the slide 62 and the gage 50 to maintain

it in contact with the top of the pad box. The upper surfaces of the gages 50 are provided with sharp inwardly projecting lips 71 arranged to engage and to penetrate the edge faces of the sole slightly thereby to hold the sole in engagement with the top of the pad box. Each of the slides 62 is provided with a dovetail slot 64 to receive a bar 66. The bars 66 are provided with upwardly extending pins 72 which enter cam slots 74 formed in plates 76. Each of the plates 76 is secured to one end of a slide 78 guided for movement lengthwise of the pad box in a housing 80 secured by a bracket 82 to the adjacent portion of the plate 58. When the slide 78 is moved lengthwise of the pad box the pins 72 are caused to move laterally of the pad box so that the bars 66 and slides 62 which, as will be explained, are connected for unitary movement will move laterally of the pad box moving the gages 50 therewith. As shown in Fig. 3 the cam slots 74 in the plates 76 are inclined in opposite directions so that the gages will move toward or away from each other upon movements of the slides 78 lengthwise of the pad box by mechanism described below.

Journalized in the forward ends of the housings 80 is a shaft 84 carrying pinions 86 which are in engagement with rack bars 88 (Fig. 4) formed in the adjacent ends of the slides 78. The shaft 84 is provided with a thumb head 90 by which the shaft may be turned thereby causing simultaneous movement of the slides 78 lengthwise of the pad box and movement of the gages 50 toward or away from each other. Also carried by the shaft 84 is a sleeve 92 carrying a pinion 94 which is arranged, as will be explained, to cause adjustment of the gage 52 lengthwise of the pad box. Integral with the sleeve 92 is a flange 96 positioned adjacent to a collar 98 held by a set screw 100 on the shaft 84 for turning movement therewith. The flange 96 is secured to the collar 98 by a screw 102. The collar 98 and with it the sleeve 92 may be adjusted relatively to the shaft 84 and held in adjusted position by the set screw 100. Thus the pinion 94 is held fast on the shaft 84 in any one of a plurality of positions for a purpose which will appear as the description proceeds.

Secured to the plate 58 is a bracket 104 which extends beyond the toe end of the pad box and has a slideway to receive a slide 106 the under surface of which is provided with rack teeth 108 (Fig. 5) engageable with the pinion 94. Secured to the top of the slide 106 is a thin plate 110 to which is secured the gage member 54. Thus it will be seen that upon rotation of the shaft 84 to move the gages 50 laterally of the pad box the gage member 54 will simultaneously be moved lengthwise of the pad box. Pivoted on studs 112 carried by the gage member 54 are laterally extending arms 114, 116 which terminate in the gage members 56. The arm 116 has a recess 118 to receive a spherical extension 120 of the arm 114, so that the arms are interconnected for equal and opposite movements. Pins 122 projecting upwardly from the gage members 56 are acted upon by a spring 124 the central portion of which is fastened to the underside of the gage member 54. This spring acts to move the gage members 56 inwardly toward each other but when a sole is presented between them they will be forced apart by the sole until the toe end contacts the gage member 54. This gage member (Fig. 5) is provided with a lip 71 similar to the lips on the gages 50.

In positioning a sole on the pad box the shaft

84 is first turned by the head 88 in a direction to move the gage 52 forwardly of the pad box and to move the gages 58 outwardly thereof sufficiently to permit placing an outsole O on the pad. The sole will be placed by the operator in the approximate position it is to occupy in the sole-attaching operation whereupon the operator will turn the shaft 84 in a direction to move the gages 58 toward each other and to move the gage 52 toward the toe end of the sole. The shaft 84 will be thus moved until the sole is contacted and properly positioned by the three gages whereupon further movement of the gages by the shaft is prevented. The inclination of the cam slots 74 is such that the movements of the toe gage and the side gages will be in the correct proportions to locate the sole with the center of the ball line in a predetermined position on the pad box regardless of the length of the sole. The gage members 56 in cooperation with the gage member 54 and the side gages 58 position the sole in the proper angular position on the pad box.

For different widths of soles having the same length, adjustment of the side gages must be made with respect to the toe gage in order that the soles will be correctly positioned lengthwise of the pad box. Threaded into the outer ends of the bars 66 are screws 126 which carry collars 128 receivable in slots 130 near the outer ends of the slides 62. The screws 126 are provided with thumb heads 132 to facilitate their rotation. When one of the screws is rotated, the bar 66 will be held against movement by the pin 72 contacting the sides of the slot 74 and consequently the slide 62 by which the gage 58 is carried will move relatively to the bar 66 thereby varying the position of the gage with respect to the pin 72. Should it be necessary for any reason to adjust the position of the toe gage 52 relatively to the machine the screw 100 is loosened and sleeve 82 turned relatively to the shaft 84 until the gage 52 is in the desired position whereupon the collar 88 is again secured to the shaft 84 by the screw 100.

The shoe to which the sole is to be attached is held in elevated position above and in register with the sole so that a cement-activating member may be positioned between the sole and the shoe to activate the cement on the attaching faces thereof, after which the activating member is moved out of the way to permit the sole to be pressed against the shoe bottom. The jack 18 (Fig. 1) at each station of the machine by which the shoe is supported comprises a forepart support 134 and a heel support 136. The forepart support includes a toe pad 138 (Fig. 7) and a welt holddown 140 which also serves prior to the sole-attaching operation to support the shoe above and in register with the sole. The toe pad 138 is secured to the lower end of a rod 142 forming a depending extension of a post 144 which is mounted for horizontal adjustment on a crosshead 146 (Fig. 2) carried by the rods 18. A setscrew 148 clamps the post in the proper position of adjustment on the crosshead which remains fixed during the normal operation of the machine.

Slidable on the rod 142 is a supporting block 150 (Figs. 2 and 7) extending outwardly from opposite sides of which are pivot pins 152. Supported on these pins are bearing members 154 to the under sides of which is secured a supporting plate 156 which in turn carries a support 158 for the welt holddown. Provision is made

for controlling the relative heights of the welt support 140 and the toe pad 138 to accommodate shoes of different styles. For this purpose a bracket 160 is secured to the lower end of the post 144 and carries an abutment screw 162 (Fig. 2) which bears against the top of the supporting block 150. A spring 164 (Fig. 7) interposed between the toe pad and the lower side of the supporting block holds the block against the lower end of the screw 162. By turning the screw the position of the supporting block 150 along the rod 142 may be varied thus adjusting the relative heightwise positions of the welt hold-down and the toe pad.

The welt holddown 140 may consist of a plurality of concavo-convex cylindrically curved plates which are held in nested relation by a cable passing through them and springs which yieldingly hold the plates in contact with one another. The lower ends of the plates are so shaped that they will enter the welt crease of the shoe S as shown in Fig. 7. For a complete description of the construction of the welt holddown reference may be made to Letters Patent of the United States, No. 2,444,969, granted July 13, 1948, in the name of C. K. Woodman. The welt holddown is so carried by the support 158 that its position relatively thereto may be adjusted in accordance with the size of the shoe to be operated upon in such a manner that the shoe will be supported in register with the outsole O on the pad box. To accomplish this the lateral positions of the ends of the welt support must be adjusted in a manner corresponding to the lateral adjustments of the gages 58 (Fig. 3) to compensate for changes in width which occur in different sizes of shoes. Furthermore in order to position the shoe lengthwise in the correct location one end of the welt support will be moved lengthwise to vary the wrap of the welt holddown around the forepart of the shoe. The means by which the welt holddown is supported and adjusted will now be described.

One end of the welt holddown is supported for adjustment laterally of the pad by a slide 166 (Fig. 7) dovetailed to the support 158. The holddown is provided with an ear 168 through which upwardly passes a headed pin 170 which also passes through the slide 166, the support 158 being recessed at 172 to accommodate the upper end of the pin which is held by a cotter pin 173 thereby to maintain the parts in assembled relation. Located above the welt holddown is a generally U-shaped rubber block 174 which occupies the space between the top of the holddown and the plate 156 and provides a yielding backing for the welt holddown. The block 174 is slotted at 175 (Fig. 8) to permit change of its shape in accordance with adjustments of the welt holddown. To one end of the block 174 (Fig. 7) is secured an ear 176 through which passes the pin 170 so that the adjacent ends of the welt holddown and the rubber block will move together in unison upon movement of the slide 166 laterally of the pad box.

Fitted into the bottom of the slide 166 is a bar 178 having an upwardly extending flange received in a groove 180 in the head of an adjusting screw 182. This screw is threaded into the slide 166 and serves to connect the slide and the bar 178 together for unitary movement and to permit adjustment of these members with respect to each other. The purpose of the bar 178 will appear as the description proceeds. The other end of the welt holddown is mounted

for movement laterally of the pad box and longitudinally thereof. For this purpose (Fig. 7) it is connected by a pin 184 passing through an ear 186 on the holddown and through a plate 188, the pin being held in place by a cotter pin 189. The plate 188 is in turn secured by a screw 190 to one end of a slide bar 192 (Fig. 8) movable lengthwise of the pad box. A slide 194 movable laterally of the pad box has a depending finger 196 which bears against the adjacent portion of the welt holddown to move it laterally of the pad box, the adjacent end of the slide bar 192 being capable of similar movement. Like the slide 166 the slide 194 is provided with a bar 198 connected by a screw 200 to the slide for adjustment relatively thereto. The adjacent end of the rubber block 174 is secured to the adjacent portion of the slide bar 192.

To maintain the welt holddown in the desired shape a pair of curved plates 202, 204 (Figs. 7, 8 and 9) are provided, these plates being pivoted together at their forward ends by a pin 206, their other ends having cam slots 208 through which pass studs 210 threaded into the bars 178, 198. The plates 202, 204 are also provided with cam slots 212 through which pass studs 214 threaded into the bottom of the support 158. The arrangement is such that as the pin 206 connecting the plates 202, 204 is adjusted lengthwise of the pad box by means to be described, the studs 214 by their cooperation with the cam slots 212 cause the opposite ends of the plates to move toward or away from each other. By this movement and because of their connection by the studs 210 and bars 178, 198 with the slides 166, 194, these slides will be moved laterally of the pad box to determine the spacing between the ends of the holddown.

Adjustment of the plates 202, 204 and the welt holddown with the rubber block 174 is effected by a lever 216 pivoted at one end on a pin 218 within the support 158. This lever is curved around the toe end of the support and at its other end is provided with a handle 220 by which it may be rocked about the pivot pin 218. The handle carries a detent 222 urged by a spring 224 into engagement with a series of teeth of a segment 226 (Figs. 2 and 8) on the support 158. The handle is cut away at 223 to expose the tooth on the detent 222 and suitable indicia 227 are provided on the segment 226 to enable the operator to move the handle 220 into the proper position for the size of the shoe to be operated upon. A knob 228 secured to the detent is provided to enable the operator to retract the detent against the action of the spring 224 to permit adjustment of the lever 216.

An intermediate portion of the lever 216 is slotted at 230 and through this slot passes a pin 232 connected to a slide 234 movable in a guide 235 formed in the support 158. The inner end of which receives the pivot pin 206 connecting the plates 202, 204. The slide 234 is actually formed of two parts similar to the slide 166 and bar 178 of Fig. 7, the parts being connected by a screw 236 thereby to permit adjustment of the distance between the pin 232 and the pivot pin 206. It will be seen that as the lever 216 is turned about the pin 218 the slide 234 will move lengthwise of the pad box causing the adjacent ends of the plates 202, 204 to move lengthwise and the other ends to move toward or away from each other thus effecting a change in the distance between the ends of the welt holddown.

The movement of the lever 216 is also utilized

to move the slide bar 192 lengthwise of the pad box and with it the adjacent end of the welt holddown, thereby to control the position of the toe end of the shoe carried by the holddown relatively to the pad box. For this purpose a link 238 (Figs. 8 and 9) is pivoted to the support 158 by a screw 240 and this link curves around the toe end of the support 158. Intermediate its ends the link has a slotted portion 242 through which passes the pin 232 whereby the link 238 will be turned about the pivot 240 upon movement of the handle 220. At its end remote from the pivot 240 the link 238 has a slotted portion 244 to which is pivoted a link 246 by a screw 248. The link 246 is connected at its other end to the slide bar 192 so that upon movement of the link about the pivot 240 the slide bar 192 will be moved lengthwise of the pad box. The slot 244 and screw 248 permit an adjustment of the link 246 with respect to the adjacent end of the lever 238 so that the lengthwise position of the slide bar 192 for any position of the adjusting lever 216 may be varied.

The heel end of the shoe is carried by the support 136 which includes a pin 250 (Figs. 2 and 2a) engageable with the hole in the heel end of the last. This pin depends from a plate 252 carried by a holder 254 which is in turn carried for vertical adjustment by a supporting block 256 slidably mounted on the crosshead 146. The supporting block 256 has a pair of inclined guideways 258 formed in opposite sides to receive flanges 260 (Fig. 2a) at the upper end of the holder 254. The lower end of the block 256 is provided with teeth 262 arranged for engagement with teeth formed in the adjacent surface of the holder 254. The heightwise dimension of the flanges 260 is somewhat less than that of the guideways 258 so that a slight vertical movement between the holder and the supporting block 256 for any position of the holder lengthwise of the block is permitted whereupon the cooperating teeth of the holder and block may be separated and the holder moved lengthwise of the block. The holder is normally held with its teeth in engagement with the teeth 262 of the supporting block by springs 264 (Fig. 2a) acting through pins 265 in vertical bores in the flanges 260. These pins are held in engagement with the bottoms of the guideways by the springs 264 the upper ends of which bear against plugs 268 threaded in the upper ends of the bores.

From the above it will be seen that if the holder 254 is moved downwardly against the action of the springs 268 to separate the teeth on the holder 254 and the block 256, the holder may be moved lengthwise of the block thereby to vary its heightwise position relatively thereto. After the holder has been properly adjusted in accordance with the heel height of the shoe to which the sole is to be attached, the springs 264, acting through the pins 266, will raise the holder into locking engagement with the teeth 262 of the block. For moving the holder lengthwise of the block an adjusting handle 270 is provided. This handle is mounted on a shaft 272 journaled in the supporting block, and to the shaft is connected an arm 274 which is in turn connected by a link 276 to the holder 254. A pointer 278 carried by the shaft 272 cooperates with indicia 280 on the block 256 to assist the operator in correctly positioning the holder relatively to the supporting block.

For activating the cement on the attaching surfaces of the sole and shoe, an activator or heater 282 (Figs. 2 and 6) is carried by one of the posts

16 for swinging movement into and out of operative position above the pad box. This activator is in the form of a manifold in the top and bottom faces of which are provided slits 284 for the emission of hot air onto the adjacent surfaces of the sole and shoe bottom. Within the manifold is mounted an electrical heating unit 286 for heating the air before it passes from the slits 284. A pipe 288 conducts the air into the manifold and this air may be preheated in any suitable manner so that it will be at a sufficiently high temperature when it leaves the manifold to soften the adhesive on the sole and shoe bottom. The manifold is provided with a handle 290 by which it may be swung about the post 16.

As illustrated most clearly in Fig. 6a the post 16 is provided with a collar 292 to which is pivoted a bell crank lever 294 one arm of which is in the form of a latch 296. This latch cooperates with a plate 298 secured to a sleeve 300 journaled on the post 16 and being formed at the end of an arm 302 (Fig. 6) secured to the activator 282. A spring 304 acts to hold the latch 296 in position to engage the lower end of the plate 298 when the activator is swung into operative position above the pad box thereby locking it in this position. At the conclusion of the activating period the bell crank lever 294 is moved against the force of the spring 304 to free the latch 296 from the plate 298 whereupon the activator is free to be swung out from between the sole and shoe bottom. To free the latch, the lower end of the arm 294 has pivoted to it a horizontal bar 306 extending to the front of the machine and being guided by a bracket 308 (Figs. 2 and 6). By pushing bar 306 rearwardly, the arm 294 swings the latch 296 downwardly to permit swinging movement of the activator into inoperative position.

In the operation of the machine preliminary adjustments will be made for the width of the shoe to which the soles are to be attached. This is effected by turning the screws 126 (Fig. 3) to position the gages 50 laterally of the pad box in accordance with the width of shoe to be operated upon. After this adjustment has been made the gages associated with the pad box are ready to receive soles of any size in that width. The thumb head 90 is first turned to retract the side and toe gages and a sole placed on the pad box between them. The head 90 is now turned in the opposite direction until all the gages contact the periphery of the sole which is thereby properly positioned on the pad box.

The handle 220 (Fig. 8) is moved into the proper position according to the size of shoe to be operated upon, the screws 200 having first been adjusted in like manner to the screws 132 (Fig. 3) according to the width of shoe. The movement of the handle 220 varies the positions of the ends of the welt holdown 140 (Fig. 7) laterally of the pad box and one end of the welt holdown lengthwise of the pad box. The forepart is inserted as shown in Fig. 7 in the welt holdown which thus determines the lengthwise and lateral positions of the shoe with respect to the pad box after which the heel end of the last is placed over the last pin 250 (Fig. 2), the heel support being properly adjusted first, if necessary. If the handle 220 has been set in the proper position for the size of the shoe the shoe will be registered accurately with the outsole. The activator is now moved into position between the outsole and shoe bottom whereupon the hot air passing from the slits in the manifold heats and

softens the thermoplastic adhesive on the attaching surfaces of the sole and shoe. After the activation is complete the activator is swung out of the way, the machine is treaded, and the pad box is moved upwardly to carry the sole into engagement with the bottom of the shoe against which it is pressed with a heavy pressure. The same operation is now repeated at the other station of the machine after which the first shoe with the sole attached thereto may be removed for succeeding shoemaking operations.

Having thus described the invention, what I claim as new and desire to secure by Letters Patent of the United States is:

15. In a machine for attaching soles to shoe bottoms, a sole-supporting pad, gages arranged for engagement with opposite side edges of a sole to determine its position widthwise of the pad, a gage arranged for engagement with the toe end of the sole to determine its position lengthwise of the pad, means for simultaneously adjusting said gages to position soles of different lengths in a predetermined location on said pad, and means for adjusting said side gages independently of said toe gage to accommodate soles of different widths.
20. In a machine for attaching soles to shoe bottoms, a sole-supporting pad, gages arranged for engagement with opposite side edges of a sole to determine its position widthwise of the pad, a gage arranged for engagement with the toe end of the sole to determine its position lengthwise of the pad, and means for simultaneously adjusting said gages to position soles of different lengths in a predetermined location on said pad, said toe gage including gage members cooperating with said side gages for determining the angular position of the sole on the pad.
25. In a machine for attaching soles to shoe bottoms, a sole-supporting pad, gages arranged for engagement with opposite side edges of a sole to determine its position widthwise of the pad, a gage arranged for engagement with the toe end of the sole to determine its position lengthwise of the pad, and means for simultaneously adjusting said gages to position soles of different lengths in a predetermined location on said pad, said toe gage including a pair of gage members engageable with opposite sides of the toe end of the sole, spring means urging said gage members toward each other, and means connecting said gage members for equal and opposite movements.
30. In a machine for attaching soles to shoe bottoms, a sole-supporting pad, gages arranged for engagement with opposite edges of a sole near the ball line, means mounting said gages for sliding movement laterally of the pad, a gage arranged for engagement with the toe end of the sole, means mounting said gage for sliding movement lengthwise of the pad, means interconnecting all of said gages for simultaneous movements coextensive as to time inwardly or outwardly of the pad, and means for thus moving said gages.
35. In a machine for attaching soles to shoe bottoms, a sole-supporting pad, gages arranged for engagement with opposite edges of a sole near the ball line, means mounting said gages for sliding movement laterally of the pad, a gage arranged for engagement with the toe end of the sole, means mounting said gage for sliding movement lengthwise of the pad, means for simultaneously moving said side gages toward or away from each other, and means operated by
40. 75. In a machine for attaching soles to shoe bottoms, a sole-supporting pad, gages arranged for engagement with opposite edges of a sole near the ball line, means mounting said gages for sliding movement laterally of the pad, a gage arranged for engagement with the toe end of the sole, means mounting said gage for sliding movement lengthwise of the pad, means for simultaneously moving said side gages toward or away from each other, and means operated by
45. 75. In a machine for attaching soles to shoe bottoms, a sole-supporting pad, gages arranged for engagement with opposite edges of a sole near the ball line, means mounting said gages for sliding movement laterally of the pad, a gage arranged for engagement with the toe end of the sole, means mounting said gage for sliding movement lengthwise of the pad, means for simultaneously moving said side gages toward or away from each other, and means operated by
50. 75. In a machine for attaching soles to shoe bottoms, a sole-supporting pad, gages arranged for engagement with opposite edges of a sole near the ball line, means mounting said gages for sliding movement laterally of the pad, a gage arranged for engagement with the toe end of the sole, means mounting said gage for sliding movement lengthwise of the pad, means for simultaneously moving said side gages toward or away from each other, and means operated by
55. 75. In a machine for attaching soles to shoe bottoms, a sole-supporting pad, gages arranged for engagement with opposite edges of a sole near the ball line, means mounting said gages for sliding movement laterally of the pad, a gage arranged for engagement with the toe end of the sole, means mounting said gage for sliding movement lengthwise of the pad, means for simultaneously moving said side gages toward or away from each other, and means operated by
60. 75. In a machine for attaching soles to shoe bottoms, a sole-supporting pad, gages arranged for engagement with opposite edges of a sole near the ball line, means mounting said gages for sliding movement laterally of the pad, a gage arranged for engagement with the toe end of the sole, means mounting said gage for sliding movement lengthwise of the pad, means for simultaneously moving said side gages toward or away from each other, and means operated by
65. 75. In a machine for attaching soles to shoe bottoms, a sole-supporting pad, gages arranged for engagement with opposite edges of a sole near the ball line, means mounting said gages for sliding movement laterally of the pad, a gage arranged for engagement with the toe end of the sole, means mounting said gage for sliding movement lengthwise of the pad, means for simultaneously moving said side gages toward or away from each other, and means operated by
70. 75. In a machine for attaching soles to shoe bottoms, a sole-supporting pad, gages arranged for engagement with opposite edges of a sole near the ball line, means mounting said gages for sliding movement laterally of the pad, a gage arranged for engagement with the toe end of the sole, means mounting said gage for sliding movement lengthwise of the pad, means for simultaneously moving said side gages toward or away from each other, and means operated by
75. 75. In a machine for attaching soles to shoe bottoms, a sole-supporting pad, gages arranged for engagement with opposite edges of a sole near the ball line, means mounting said gages for sliding movement laterally of the pad, a gage arranged for engagement with the toe end of the sole, means mounting said gage for sliding movement lengthwise of the pad, means for simultaneously moving said side gages toward or away from each other, and means operated by

in a manner to position soles of different sizes in the same relative position on said pad.

6. In a machine for attaching soles to shoe bottoms, a sole-supporting pad, gages arranged for engagement with opposite edges of a sole near the ball line, means mounting said gages for sliding movement laterally of the pad, a gage arranged for engagement with the toe end of the sole, means mounting said gage for sliding movement lengthwise of the pad, means for simultaneously moving said side gages toward or away from each other, means operated by said last-named means for moving said toe gage in a manner to position soles of different sizes in the same relative position on said pad, and means associated with said toe gage cooperating with said side gages for controlling the angular position of the sole on the pad.

7. In a machine for attaching soles to shoe bottoms, a sole-supporting pad, gages arranged for engagement with opposite edges of a sole near the ball line, means mounting said gages for sliding movement laterally of the pad, a gage arranged for engagement with the toe end of the sole, means mounting said gage for sliding movement lengthwise of the pad, means for simultaneously moving said side gages toward or away from each other, means operated by said last-named means for moving said toe gage in a manner to position soles of different sizes in the same relative position on said pad, and means for adjusting said side gages relatively to said moving means.

8. In a machine for attaching soles to shoe bottoms, a sole-supporting pad, gages arranged for engagement with opposite edges of a sole near the ball line, means mounting said gages for sliding movement laterally of the pad, a gage arranged for engagement with the toe end of the sole, means mounting said gage for sliding movement lengthwise of the pad, a shaft extending transversely of the pad forwardly of the toe end, a pinion carried by said shaft intermediate its ends, rack teeth on said toe gage engageable with said pinion, pinions carried at opposite ends of said shaft, racks extending lengthwise of the pad box at opposite sides thereof engageable with said pinions, plates carried by said racks overlying the pad adjacent to said side gages, cam slots in said plates inclined oppositely to each other, and pins connected to said side gages received by said cam slots whereby the side gages are moved toward and away from each other upon turning of said shaft and the toe gage is simultaneously moved lengthwise of the pad.

9. In a machine for attaching soles to shoe bottoms, a sole-supporting pad, gages arranged for engagement with opposite edges of a sole near the ball line, means mounting said gages for sliding movement laterally of the pad, a gage arranged for engagement with the toe end of the sole, means mounting said gage for sliding movement lengthwise of the pad, a shaft extending transversely of the pad forwardly of the toe end, a pinion carried by said shaft intermediate its ends, rack teeth on said toe gage engageable with said pinion, pinions carried at opposite ends of said shaft, racks extending lengthwise of the pad box at opposite sides thereof engageable with said pinions, plates carried by said racks overlying the pad adjacent to said side gages, cam slots in said plates inclined oppositely to each other, pins connected to said side gages received by said cam slots whereby the side gages are moved toward and away from each other upon

turning of said shaft and the toe gage is simultaneously moved lengthwise of the pad, and means for adjusting the sole contacting portion of each of the side gages with respect to the pin associated therewith.

5 10. In a machine for attaching soles to shoe bottoms, a sole-supporting pad, gages arranged for engagement with opposite edges of a sole near the ball line, means mounting said gages for sliding movement laterally of the pad, a gage arranged for engagement with the toe end of the sole, means mounting said gage for sliding movement lengthwise of the pad, a shaft extending transversely of the pad forwardly of the toe end, a pinion carried by said shaft intermediate its ends, rack teeth on said toe gage engageable with said pinion, pinions carried at opposite ends of said shaft, racks extending lengthwise of the pad box at opposite sides thereof engageable with said pinions, plates carried by said racks overlying the pad adjacent to said side gages, cam slots in said plates inclined oppositely to each other, pins connected to said side gages received by said cam slots whereby the side gages are moved toward and away from each other upon turning of said shaft and the toe gage is simultaneously moved lengthwise of the pad, gage members pivoted to said toe gage and arranged to engage opposite side edges of the sole adjacent to the toe end, springs acting on said gage members for moving them toward each other, and means connecting said gage members for equal and opposite movements.

20 11. In combination, a sole-supporting pad, gages associated with said pad, means for operating said gages to position automatically soles of different sizes on said pad with a reference point within the sole at a predetermined position on the pad, means for supporting a shoe above and 30 in register with the sole on the pad, and means for pressing the sole against the shoe bottom.

25 12. In combination, a sole-supporting pad, gages associated with said pad, means for operating said gages to position automatically soles of different sizes on the pad with a reference point within the sole at a predetermined position on the pad, means for supporting a shoe above a sole on said pad, said supporting means comprising means for positioning the shoe in a 40 predetermined relation to the sole on the pad, and means for moving said pad and said supporting means one with respect to the other to press the sole against the shoe bottom.

35 13. In a machine for attaching soles to shoe bottoms, a sole-supporting pad, means for locating a sole in a predetermined position on said pad, means for supporting a shoe in spaced relation above said pad and in register with a sole thereon, means for heating the attaching faces of the sole 50 and shoe while the shoe is thus supported, and means for then moving the shoe-supporting pad and the sole-supporting means one with respect to the other to press the sole against the shoe bottom.

45 14. In combination, a sole-supporting pad, gages associated therewith, means for operating said gages to position automatically soles of different sizes on the pad with a reference point within the sole at a predetermined position on the pad, means for supporting a shoe above and 60 in spaced relation to a sole on said pad, said supporting means comprising means for positioning the shoe in register with the sole on the pad, a heater, means mounting said heater for movement into and out of operative position between 70 75

the pad and the shoe-supporting means, said heater being arranged when in operative position to heat the attaching faces of the sole and shoe bottom, and means for moving the pad and shoe-supporting means one with respect to the other after the heater is moved into inoperative position to press the sole against the shoe bottom.

15. A machine for attaching soles to shoe bottoms comprising a sole-supporting pad, gages associated therewith, means for operating said gages to position automatically soles of different sizes on said pad with the center of the sole at the ball line in a predetermined position on the pad, means for supporting a shoe in register with the sole on the pad, said shoe-supporting means including a holddown engageable with the welt to sustain it against upward pressure during the sole-attaching operation, and means for moving the pad and the shoe-supporting means one with respect to the other to press the sole against the shoe bottom.

16. A machine for attaching soles to shoe bottoms comprising a sole-supporting pad, gages associated therewith for positioning soles of different sizes on said pad with the center of the sole at the ball line in a predetermined position on the pad, means for supporting a shoe in register with the sole on the pad, said shoe-supporting means including a holddown engageable with the welt to sustain it against upward pressure during the sole-attaching operation, means mounting said holddown for adjustment widthwise and lengthwise of the supporting means to determine the position of the shoe with respect to the sole on the pad, and means for moving said pad and said supporting means one with respect to the other to press the sole against the shoe bottom.

17. In a machine for attaching soles to the bottoms of welt shoes, sole-supporting means, gage means associated therewith for locating a sole on the supporting means, means for supporting a shoe in spaced relation to a sole on the sole-supporting means, means associated with said shoe supporting means for locating the shoe in register with the sole on the supporting means, said last named means including means engageable with the top face of the welt to sustain it against the sole-attaching pressure, a heater movable into and out of the space between the sole and shoe and arranged to heat the attaching faces of the sole and shoe when positioned between the sole and shoe, and means for causing relative movements of said supporting means after the heater has been moved out of said position for pressing the sole against the shoe bottom.

18. In a machine for attaching soles to the bottoms of welt shoes, a welt holddown arranged to support a shoe in a predetermined position in spaced relation above a sole to be attached to the shoe bottom and to sustain the welt against the sole-attaching pressure, said welt holddown comprising a flexible member having a portion engageable in the welt crease of the shoe around the forepart thereof and rearwardly to the ball line, and means mounting said holddown for adjustment in accordance with the size of the shoe to which a sole is to be attached.

19. In a machine for attaching soles to the bottoms of welt shoes, a welt holddown arranged to support a shoe in a predetermined position in spaced relation above a sole to be attached to the shoe bottom and to sustain the welt against the sole-attaching pressure, said welt holddown comprising a flexible member having a portion engageable in the welt crease of the shoe around the

forepart thereof and rearwardly to the ball line, and means mounting the ends of said holddown for adjustment widthwise of the shoe to be operated upon.

20. In a machine for attaching soles to the bottoms of welt shoes, a welt holddown arranged to support a shoe in a predetermined position in spaced relation above a sole to be attached to the shoe bottom and to sustain the welt against the sole-attaching pressure, said welt holddown comprising a flexible member having a portion engageable in the welt crease of a shoe around the forepart and rearwardly to the ball line at each side, means mounting one end of said holddown for adjustment widthwise of the shoe to be operated upon, and means mounting the other end of said holddown for adjustment widthwise and lengthwise of the shoe.

21. In a machine for attaching soles to the bottoms of welt shoes, a welt holddown arranged to support a shoe in a predetermined position in spaced relation above a sole to be attached to the shoe bottom and to sustain the welt against the sole-attaching pressure, said welt holddown comprising a flexible member having a portion engageable in the welt crease of a shoe around the forepart and rearwardly to the ball line at each side, means mounting one end of said holddown for adjustment widthwise of the shoe to be operated upon, means mounting the other end of said holddown for adjustment widthwise and lengthwise of the shoe, and single means for effecting all of said adjustments.

22. In a machine for attaching soles to the bottoms of welt shoes, a welt holddown comprising a plurality of flexibly-connected welt-engaging members each of which has a portion arranged to engage the welt crease of a shoe around the forepart, means supporting said members for relative heightwise movements, a pair of curved plates engaging the outer periphery of said holddown, means pivoting said plates together at the toe end, and means for adjusting said plates to vary the contour of the holddown in accordance with the size of the shoe to be operated upon.

23. In a machine for attaching soles to the bottoms of welt shoes, a welt holddown comprising a plurality of flexibly-connected welt-engaging members each of which has a portion arranged to engage the welt crease of a shoe around the forepart, a pair of curved plates engaging the outer periphery of said holddown, means pivoting said plates together at the toe end, means for moving said pivoting means lengthwise of the shoe to be supported by the holddown, and means causing the outer ends of said plates to move toward or away from each other in response to such movement of the pivoting means thereby to adjust the contour of the holddown in accordance with the size of the shoe to be operated upon.

24. In a machine for attaching soles to the bottoms of welt shoes, a welt holddown comprising a plurality of flexibly-connected welt-engaging members each of which has a portion arranged to engage the welt crease of a shoe around the forepart, a pair of curved plates engaging the outer periphery of said holddown, means pivoting said plates together at the toe end, means for moving said pivoting means lengthwise of the shoe to be supported by the holddown, means causing the outer ends of said plates to move toward or away from each other in response to such movement of the pivoting means thereby to adjust the contour of the holddown in accordance with the size of the shoe to be operated upon,

15

and means operated by said pivot moving means for moving one end of said welt holddown lengthwise of the shoe carried thereby.

25. In a machine for attaching soles to the bottoms of welt shoes, a welt holddown comprising a plurality of flexibly-connected welt-engaging members each of which has a portion arranged to engage the welt crease of a shoe around the forepart, a pair of curved plates engaging the outer periphery of said holddown, means pivoting 10 said plates together at the toe end, means for moving said pivoting means lengthwise of the shoe to be supported by the holddown, means causing the outer ends of said plates to move toward or away from each other in response to 15 such movement of the pivoting means thereby to adjust the contour of the holddown in accordance with the size of the shoe to be operated upon, and

16

means for moving the ends of said welt holddown relatively to said plates.

PAUL W. SENFLEBEN.
